US0D1112331S

(12) **United States Design Patent** (10) **Patent No.:** **US D1,112,331 S**
Shawish (45) **Date of Patent:** **** Feb. 10, 2026**

(54) **DISPLAY SCREEN OR PORTION THEREOF WITH GRAPHICAL USER INTERFACE**

(71) Applicant: **Waters Technologies Ireland Limited, Dublin (IE)**

(72) Inventor: **Fadi J. Shawish, Pawtucket, RI (US)**

(73) Assignee: **Waters Technologies Ireland Limited, Dublin (IE)**

(**) Term: **15 Years**

(21) Appl. No.: **29/887,187**

(22) Filed: **Mar. 17, 2023**

(51) LOC (15) Cl. **14-04**

(52) U.S. Cl.

USPC **D14/486; D14/492**

(57) **CLAIM**

The ornamental design for a display screen or portion thereof with graphical user interface, as shown and described.

DESCRIPTION

The FIGURE is a front view of a display screen or portion thereof with a graphical user interface.

The elements shown in gray lines illustrate portions of the graphical user interface and are part of the claimed design. The outermost broken lines showing a display screen or portion thereof illustrate portions of the article and form no part of the claimed design.
